UNITED STATES PATENT OFFICE.

MICHAEL J. GREUBEL, OF NORTH PLAINFIELD, NEW JERSEY.

CASE.

Application filed April 6, 1926. Serial No. 100,007.

My invention relates to cases to preserve small articles from damp and wet, such as are particularly useful to bathers, hunters, fishermen, etc. The construction is such that 5 wet and damp may be thoroughly excluded, and at the same time the articles in the case are held readily available for use.

The accompanying drawing illustrates my invention applied to a case for cigarettes and 10 matches; it will be apparent however, that it may be used for other things at will. Fig. 1 is a perspective view of the closed case attached to the owner's belt.

Fig. 2 is also a perspective view of the 15 same, but illustrating the two component parts or sections of the case separated.

Fig. 3 is a sectional view of the closed case.

Fig. 4 is a repetition of a part of Fig. 3 20 on a larger scale, but showing one of the latches released from its catch.

Fig. 5 is a perspective of the carrier section of the case, showing the two component parts of the section separated.

25 Fig. 6 is a sectional view of the carrier section on the line VI—VI of Fig. 3.

Fig. 7 is a detail.

Fig. 8 is a detail of a modification of the latch, and

30 Fig. 9 is a detail of a slight modification.

The case of my invention, as illustrated, comprises two entirely separable components or sections, one of which, the cover 1, I term the belt section inasmuch as the case is designed for attachment to the wearer's belt; the other section 2 is a carrier section which supports or holds the articles to be encased. The cover or belt section 1 comprises not only an extended body portion or one of the 35 large walls of the case, but usually also the major part of the side walls of the case as shown in the drawings. For attachment to the belt, a loop 5 is fastened to the body or large wall of the belt section. This may 40 have the ordinary form of loops for this purpose but many belts for bathing suits, etc., are now made with a part of the belt buckle or clasp attached to each end of the fabric, which makes it difficult to slip the 45 belt endwise through such a loop. Accordingly I may cut the loop through the center, longitudinally of the belt, as shown in Fig. 50 5, separating the two portions of the loop about one-eighth of an inch at the center,

through which opening the body of the belt 55 can be worked into the loop, so that it is unnecessary to introduce the belt endwise.

To make the case water-tight, I provide a groove adjacent the rim of the cover or belt section, i. e., in the edge of the side wall or 60

walls (Figs. 3 and 4) to receive a lip on the opposite section, and cam clamping means to press the lip tightly into the groove. A gasket 4 can be interposed in the groove. Such a groove can be provided in various 65 ways as will be apparent, but I do this preferably by the use of spaced double side walls 6—7, as by forming the section of two nesting boxes (see Figs. 3 and 4) having similar body or large-wall portions and parallel side 70 walls 6 and 7 of sheet metal. The inner wall 7 of the double wall is bent back upon itself at the box opening as indicated at 8, and then extended outwardly into a flange 9 reaching to the outer wall 6. Similarly 75 the outer walls 6 are bent back upon themselves at their outer edge, as indicated at 10, and extended into an inturned flange 11 which (when the boxes are nested) overlies the flange 9. As thus constructed, the two 80

boxes are locked together and form the unit 1. The nested boxes may be further attached together however if desired, as by sweating or welding their large-wall portions together or in any other way. It will, 85 be understood that for the greater part of the edge, the inturning of the metal of the outer box at 10 resembles the out-turning of the metal of the inner box at 8 as the latter is illustrated in Figs. 3 and 4; at desirable places however, the adjacent metal of the outer box (one or both thicknesses) may be raised up to form a suitable catch or catches 12 (compare Fig. 2 with Figs. 3 and 4), for the latch or latches hereafter referred to again. The sectional views of Figs. 3 and 4 are taken through such catches.

As before mentioned, a lip on the carrier section 2 of the case enters the groove in the belt section 1, and in order to make the correct assembly of the two sections easy to perform, I make the edge of the inner wall 7 somewhat higher than the edge of the outer wall 6, and make the flange-rim 13 of section 2 fit rather snugly (but easily) around this 90 inner higher wall. In order then to bring the edge of this rim to the center of the gasket, I turn this edge out slightly as 105

shown in Figs. 3 and 4. This also aids in guiding the carrier section rim over the edge of the inner wall 7 and into place in the groove. As shown in the drawing, this rim 13 may be provided and strengthened by in-turning and then bending back on itself a part of the sheet metal forming the base or body of the carrier section.

The cam latches 19 which lock the two component sections of the case together, are mounted on this carrier section 2, and consist of rings or other members hinged to brackets 20 extending from the edge of the carrier section to beyond the edge of the wall 6, as illustrated in various figures. The brackets 20 may be attached to or raised from the carrier section 2 in any desired way, and usually being composed of sheet metal or the like, they yield when the carrier section 15 (with the latches held in the position of Fig. 2) is seated in the cover groove, thereby permitting the latches to ride over the catches 12 and causing the latches to seat in front of the catches. However, the part or portion 20 of each latch lying in front of its catch is off-set or eccentric. Hence by turning the latches from their position in Fig. 2 to the position in Fig. 3, they are pressed tightly against the catches 12 and thereby 25 the carrier-section rim 13 is pulled tight against the gasket 4. To release the pressure the latches are turned back to their Fig. 2 position, and then, in order to get the eccentric or offset parts 21 of the latches out 30 from in front of the catches 12 to take off the carrier section, the parts 21 are to be pulled away from the wall 6. For this purpose I provide a bead 18 (usually by raising the metal) on the cover section 2 adjacent the latches. This bead may extend entirely 35 around the edge of the section, as shown. By making the latches long enough to extend well over the bead as illustrated in Fig. 4, the portions 21 of the latches can be raised out 40 of the catches 12 by prying the latches down against the bead as will be clear from this Fig. 4. By providing two of these latches and locating them on opposite sides of the case as appears in Figs. 1 and 5, it will be 45 apparent that the cover can be removed with one hand by merely squeezing on the two latches simultaneously, prying them both together against the bead 18 to the position shown in Fig. 4.

50 The articles to be carried, i. e. handkerchiefs, bathing keys, etc., may, of course, be deposited loosely in the case. Preferably however the detachable section 2 is also a carrier for the articles as before indicated, 55 containing these articles so that by simply releasing the section 21 by squeezing the two latches together as before explained, the case contents come away from the cover or belt section 1, along with the section 2. The 60 section 2 may be specially designed and

adapted interiorly for this purpose. It may be provided with a special holder for the article or articles. Thus the case illustrated being especially designed for cigarettes and matches, it is provided with a holder 25 of 70 the form illustrated particularly in Figs. 3, 5 and 6; that is to say, a four-walled container open top and bottom, and provided, if desired, with a step 26 opposite one open end. The interior of the holder 25 may be 75 just large enough to receive a full package of cigarettes snugly, and the step 26 then aids in placing the package by limiting the distance the package can be pushed in and may also act as a floor to help support the 80 cigarettes, especially when some of the cigarettes have been used and the wrapper is inclined to collapse. The holder is attached of course to the section 2 and preferably in such a manner that it can be readily removed 85 from the cover so as to increase the capacity of the case for other articles not adapted for use with the holder 25. This may be done by providing the inside wall of section 2 with rather broad short hooks 27 and one 90 of the larger surfaces of the holder 25 with loops or cuts 28 to receive the hooks 27 in the manner illustrated in Figs. 3 and 6. The hooks 27 may be raised from a narrow 95 flat piece of sheet metal fixed to the inside face of the section as illustrated in Figs. 5 and 6. The package of cigarettes is indicated at 29, and Figs. 3, 6 and 7 also illustrate how the same holder is adapted to carry a folder of matches. The side of the 100 holder 25 opposite the side having the cuts or loops 28, is made somewhat narrower than the length of the ordinary match folder (Fig. 6). By opening the folder and slipping the back of the folder between this wall 105 of the holder and the package of cigarettes, as illustrated in Fig. 6, the folder cover can be replaced again over the matches in the usual position. When the carrier section is inserted in the belt section 1, the matches 110 therefor lie between the holder 25 and the base of the belt section. It will be understood however that holders and the like, specially adapted for receiving other articles than packages of cigarettes and matches can 115 be used. If desired, the holder may be omitted from the case altogether as before indicated.

Usually I make the latch 19 of wire or small rod bent into the proper shape, as appears from various of the figures. Latches of the same shape however may be cut or otherwise formed from other metal shapes. Fig. 8, for example, illustrates such a catch formed from sheet metal by press work, expansion or otherwise. Other forms of clamping means may be substituted. Also the external dimensions of the case can be reduced without reducing the internal dimensions, by locating the walls 6 closer to 120 125 130

the walls 7 than indicated in the figures already described. Thus, for example, Fig. 9 illustrates the side wall 6 brought more directly from the gasket groove to the body or large-wall portion of the box 7; thus certain outside dimensions of the case are reduced in a pleasing manner without reducing either the inside dimensions of the case or the dimensions of the gasket groove.

10 In general indeed, my invention is subject to various modifications of the details illustrated and described above, and it will be understood accordingly that it is not limited to the details illustrated and described, except as appears in the following claims:

1. A case of the kind described comprising two sections, means for releasably holding the two sections closed one on another to encase an article, means for attaching one of said sections to the person, and a holder to contain the article carried by the other section, the case being characterized by the fact that said holder is releasable from the section by which it is carried.

25 2. The subject of claim 1, characterized by the fact that the holder is held to the section which carries it by clips, by reason of which the holder can be slipped off said section.

30 3. A case of the kind described comprising two separate sections, the first having an encircling groove at its rim and the second adapted to set in said groove, and means for fastening one section to the other comprising a catch on one section and a pivoted latch on the other section, the latch and catch being so related that the latch normally rests in front of the catch, in position to hold the two sections together, when 35 the second mentioned section rests in the said groove of the first mentioned section, and the latch having an eccentric portion to exert case-closing pressure on the catch when the latch is turned.

40 4. A case of the kind described comprising two sections, a latch on one of the sections to lock the sections closed one on the other; and a cooperating catch on the other section, one of the sections being provided 45 with means over which the latch can be pried to lift the latch from in front of the catch.

50 5. A case of the kind described comprising two sections, a latch on one of the sections to lock the sections closed one on another, and a cooperating catch on the other section, the latch normally resting in front of the catch when the sections are closed and the latch and catch being mutually so constructed that turning the latch exerts case-closing pressure on the catch, one of the sections being provided with means over which the latch can be pried to lift the latch from

in front of the catch to permit opening the case.

6: A case of the kind described comprising two sections, a latch on one section to lock the sections closed one on another, and a cooperating catch on the other section, the latch normally resting in front of the catch 70 when the sections are closed and being provided with an eccentric portion to exert case-closing pressure on the catch when the latch is turned.

7. The case of claim 6 characterized by 75 one of the sections being provided with means over which the latch can be pried to lift the latch from in front of the catch to permit opening the case.

8. The case of claim 6 characterized by the 80 section carrying the latch having a bead over which the latch can be pried to lift the latch from in front of the catch to permit opening the case.

9. A case of the kind described comprising two sections completely detachable one from the other, means for attaching one of said sections to the person, and means for fastening the two sections together in watertight relation comprising catches on opposite 90 edges of the section arranged to be attached to the person and cooperating pivoted latches at opposite edges of the other section arranged to exert case-closing pressure on the catches when turned and to be operated simultaneously by one hand of the user to release the sections one from the other. 95

10. A case-section adapted to receive a rim lip of another section in a groove at its rim and be attached thereto by a latch, said case-section having an outer wall terminating at the rim of the case-section, and a second wall extending from adjacent the floor of the case section, within said outer wall to the rim of the section, and spaced apart from the outer wall adjacent said rim to form the lip-receiving groove, one of said walls being folded to form a bottom for the groove extending to the other wall. 100

11. A case of the kind described comprising two sections, a catch on one of the sections, and a cooperating hinged latch on the other section to lock the sections closed one on the other, said latch being hinged to turn toward and from the interior of the case 110 when engaging and disengaging the catch, normally resting at the front of the catch when the sections are closed, arranged to exert case-closing pressure on the catch, and to be pried against the edge of one of the 115 sections to lift the latch in a direction from in front of the catch. 120

In testimony whereof, I have signed this specification.

MICHAEL J. GREUBEL.
